UNITED STATES PATENT OFFICE.

AMOS H. HAWLEY, OF NORWOOD, OHIO, ASSIGNOR, BY MESNE ASSIGNMENTS, TO REMINGTON ARMS COMPANY, INC., OF NEW YORK, N. Y., A CORPORATION OF DELAWARE.

ACCOUNTING MACHINE.

Application filed November 21, 1918. Serial No. 263,625.

To all whom it may concern:

Be it known that I, AMOS H. HAWLEY, citizen of the United States of America, residing at Norwood, in the county of Hamilton and State of Ohio, have invented certain new and useful Improvements in Accounting Machines, of which the following is a specification.

The present invention has to do particularly with accounting machines for adding and listing purposes and involves primarily certain improvements in machines of the type disclosed in U. S. patents of White No. 1,192,721 issued July 25, 1916, and Runquist No. 1,213,268 issued January 23, 1917.

Among the objects of the invention have been the reorganization of certain portions of the mechanism of the machine whereby I have obtained a positive actuating means for effecting release of the amount keys and the associated indexing parts, which are usually locked upon depression of said keys; the employment of peculiar interlocking instrumentalities between the total and the sub-total keys acting to avoid improper action of these keys; provisions whereby the device controlling repeat operations of the machine are improved; and special provisions whereby the totaling keys are adapted to effect release operation of the repeat key should the latter be in its depressed position or actuated position, when either the total or sub-total key is operated.

The present invention resides in other specific features of mechanism which will be more fully disclosed hereinafter, and this application constitutes a division of my pending application for patent for accounting machine, Serial No. 173,790, filed June 9, 1917.

In the accompanying drawings, Figure 1 is a right vertical sectional view through the machine embodying the improvements of this invention and bringing out the general arrangement of the key board accumulating and printing mechanisms.

Figure 2 is a vertical sectional view showing more clearly the driving connection between the main actuator shaft and the key releasing device.

Figure 3 is a view similar to Figure 2 but taken on a different vertical line of section and bringing out more fully the key release mechanism, the arrangement of the special keys and the parts interacting therebetween.

Figure 4 is a detail view showing certain parts associated with the repeat key restoring device.

Figure 5 is an isometrical view of a certain portion of the key board mechanism, 60 clearly bringing out the arrangement of the special key connections and release device.

Figure 6 is a plan view showing more particularly the key board section alone, the locking device for the keys and certain other parts being omitted for clearness, but the release bar being fully illustrated.

Figure 7 is a view of the special keys on the right hand side of the key board and shows particularly the means used to restore 70 the repeat key by manipulation of the other special keys, together with the means for positively actuating the key releasing device.

Figure 8 is a view looking from the front 75 and showing in a fragmentary manner certain members of the key releasing and the locking devices.

Figure 9 is an exploded perspective of the numeral key release means.

Figure 10 is a perspective showing the control key interlock and numeral key release actuating mechanism.

The machine to which I have adapted my improvements embodies certain adding, listing, and other auxiliary registering mechanisms presented in detail in the co-pending application for patent of Mann and Hawley, Serial No. 48,544, filed September 1, 1915, now issued as Letters Patent 1,298,751, 90 April 1, 1919. In view of the disclosures in the previously identified Letters Patent, it is not deemed necessary to recite in detail the construction and operation of the adding machine therein presented. Generally

speaking, the machine shown in the drawings annexed hereto include a main actuator in the form of a shaft 625 operated in the well-known manner, and the usual key board including rows of amount keys 100 100 with associated special operation keys. There is employed additionally known listing mechanism including type carriers and a known type of paper carriage.

The accumulator 311 is located at the front of the machine so that registrations thereof may be observed through suitable openings 311^a in the machine case. The keys 100 control the indexing mechanism for the accumulating and printing instru- 110

mentalities, in a manner substantially as set forth in the aforesaid White patent. There may be provided, as shown in Figure 6, certain special operation keys including a 5 repeat key, designated 142, an error key designated 137, a sub-total key, designated 136, and a total key, designated 135.

As seen best in Figure 1 the accumulator embodies the usual adding wheels 472, the 10 pinions of which are engageable by adding racks 301, the movement of the latter being effected by operating levers 500 connected at their front ends with adding racks, one for each rack, and at their rear ends each 15 connected with a type carrier 706. A spring 616 is connected with an arm 500" projecting downwards from the central portion of each lever 500 and normally tends to draw the front end of the lever downwards and 20 raise its rear end. Such movement of the lever 500 is restrained, however, by a restoring bar 641 contacting with the upper edge of the rear portions of the several levers and carried by a pair of arms 505 having irregular slots formed therein.

The racks 301 and type carriers 706 are adapted for differential movement under the control of the indexing mechanism, directly actuated by the keys 100. It may be noted 30 that on each actuation of the shaft 625, the governor shaft 626, to which said lever 508 is secured, will be partially rotated by means of a flexible connection comprising a spring and forked rod as clearly shown in Figure 2. 35 Affixed to the governor shaft 626 is a pair of downwardly extending arms 512 provided with studs 655, which enter the crooked slots in the arms 505. Thus the operative connection established by the parts just mentioned 40 is adapted to raise the restoring bar 641 by the aforesaid rollers 655 cooperating with the irregular slots in the bars supporting the said restoring bar 641 thereby permitting springs 616 to draw the actuating racks 301 45 downwardly to an extent to determine by the indexing mechanism when the machine is operated.

The extent of movement of the levers 500 is controlled by the keyboard mechanism including the keys 100 and suitable indexing stops 110 (see Figure 1), one of which is provided for each key 100, those for each 50 row of keys being superposed. Depression of a key 100 of a certain row forces rearwardly by means of a pin 100' the locking bar 120, disengages the front end of said bar from a projection 301' on the corresponding rack 301 and simultaneously projects forward an indexing stop 110 into the 55 path of said projection 301'. According to whichever stop 110 is rendered operative, so will be the extent of movement of the adding rack 301 and lever 500 controlled by said stop. In this way, differential movement of each lever 500 is controlled so as

to cause one or more increments of movement of the adding pinion of the associated adding wheel and corresponding movement of the type carrier to position a type of the latter at the printing point. 70

Engagement of the customary wipe pawl with the three armed lever is differentially controlled by a main total lever, an auxiliary total lever, and a sub-total lever, which are adjusted for controlling said engagement by 75 manipulation of certain special operation keys including the total, and sub-total keys. It is not believed necessary to present with detail the operation of the said levers in view of the identified White patent. 80

It will be observed that the listing mechanism is of the known type presented in the White Letters Patent and comprising a series of vertically moving type carriers 706 pivoted at their lower ends to the levers 500 85 and carrying type spaced to correspond with the predetermined degrees of movement of the levers 500. Printing impression is produced by impingement of the hammers 700 against such type as may be positioned at 90 the printing line.

It has heretofore been a practice to depend upon a spring actuated pawl carrier as a means of releasing the manipulative keys 95 upon the return of the main actuator to normal (see member 106 of Figure 15 of White patent aforesaid). This construction in practice is not altogether satisfactory in that sometimes the pawl carrier does not respond to the ordinary spring tension, due perhaps to friction on its mounting or the gumming of the lubricant used, or other causes. Therefore, as shown in Figures 2 and 7, I have provided, in the upper arm of the lever 508, a cam slot 508" adapted to receive the lateral stud 140^a carried by an arm 140' (see Figure 9) of the lever 140 which is mounted on the keyboard side plate 123^a (see Figure 8). The engagement of the stud 140^a with the slot 508" is such that as the lever 508 oscillates with the shaft 626 to which it is fixed, the stud 140^a will initially be actuated by the lever 508 to shift the lever arm 140' 100 upwards, and afterwards the stud will be carried out of the slot and then remain in engagement with the arc 508'', which forms a dwell. It is to be borne in mind that the initial movement of the main actuator causes movement of the lever 508 in the direction indicated by the arrow (see Figure 115 7); thus it is plain that upon return movement the stud 140^a will be reengaged with the upper wall of the slot 508" of the lever 508 and the pawl carrying lever 140 (see Figure 9) positively actuated through movement of the arm 140' downwards. This lever 140 carries certain key release actuating means now to be pointed out and analogous to those now known.

Referring to Figures 7 and 9, mounted on 120 125 130

the upper end of the lever 140 is the trip pawl 141 provided with a tooth 141' which is adapted to engage the stud 75 associated with the key release shaft A-261 seen in Figure 8. The pawl 141 has a stop projection 141'' which engages the ear 140'', formed on the upper end of the lever 140, and serves to hold the said pawl in operative position against the tension of the spring 141^a. The function of the repeat key is to disable the pawl 141 and the coacting shaft A-261 as is well known according to the identified White patent; the means adopted for this purpose in the present instances consists of the lever 76 mounted pivotally on the side plate 123^R and, by means of the slot 76'' and the stud 142'', connected with the repeat key 142. At the front end of the said lever 76 is a surface 76' over which the stud 141^b rides when the repeat key is depressed as shown in Figure 7. The up or inoperative position of the key 142 is shown in Figure 3. When in the latter position the key 142 permits the lever 76 to remain lowered or tilted so that the tooth 141' of the pawl 141 may engage the stud 75 of the key release shaft A-261, on the return movement of the shaft 626, thus rocking the shaft A-261 to release the keys after the ordinary manner. The positioning of the parts as in Figure 7 on depression of the key 142 simply renders the part 141' inoperative to perform the stated function. The devices which lock the total and sub-total keys against mis-operation are best shown in Figures 7 and 9. It will be observed that supported by suitable mountings on the keyboard side plate 123^R, is a slide member 166 with the two beveled projections 166' and 166'' arranged for engagement by the studs 136' and 135' projecting laterally from the sub-total and total keys respectively; these members are so proportioned that upon depression of either of the two keys 135 or 136 the member 166 will be moved away from the key depressed and into the path of the stud carried by the key not so manipulated. However, if an effort is made to depress both keys at the same time, their respective studs will engage against the bevel projections 166' and 166'' of the member 166, locking the said keys against simultaneous effective manipulation.

Referring to Figures 3 and 7, it will be noted that the keys 135 and 136 carry each a second laterally projecting stud 135'' and 136'', respectively, which normally stand above the path of the hook projections 133'' on the upper edge of the slide bar 133, but when either key is depressed, the said second stud thereon is in a position such as to permit the corresponding hook projection 133'' to pass above the said stud.

The bar 133 is positively connected with the lever 140 as shown in Figures 3, 5, 7, and

9 wherein the stud 141^c, on which the pawl 141 is carried, projects into a slot 133''' cut into the lower edge of the bar 133 establishing a permanent connection between said parts. The bar 133 is therefore positively driven in its excursions which are made upon the first and last degrees of movement of the main actuator; thus it will be understood how the keys 135 and 136 are locked against manipulation when the main actuator is positioned otherwise than at normal.

Adjacent to the slide member 166 and mounted to slide on suitable supports is the bar 77 provided with bevel projections 77' and 77'' which upon depression of the keys 135 or 136 are engaged to cause rearward movement of the bar 77, the end 77''' of which is adapted to engage the repeat key 142 at its lower end. By this action the bar 77 will rock the repeat key 142 on the stud 142^b, to disengage the same at its notch 142^x from engagement with the keyboard top plate 124. This operation permits restoring action of the spring 142^a to restore the key 142 to normal, presuming the said repeat key 142 is in the depressed position (shown in Figure 7) when the total or subtotal key is manipulated.

Figures 3, 6, and 8 show the manner in which latches such as 134 cooperate to hold the total and sub-total keys depressed; also the arrangement of the release bar 138 which cooperates with the latches 129 by which the numeral keys 100 are retained in depressed positions in the manner fully set forth in the White patent. The latches 129 are supported by suitable plates 128, the uppermost of which is shown in Figure 6.

Having thus described my invention, what is claimed as new is:—

1. In an accounting machine, the combination of accounting mechanism, a main actuator therefor, manipulative keys for predetermining the operation of the accounting mechanism, lock means to hold said keys in operated positions, a release device for said lock means, a total key to control totaling action of the accounting mechanism, and means to interfere with the release operation of the release device and controlled by the total key.

2. In an accounting machine, the combination of accounting mechanism, a main actuator therefor, manipulative keys for predetermining the operation of the accounting mechanism, lock means to hold said keys in operated positions, a release device for said lock means, a total key to control totaling action of the accounting mechanism, a repeat key settable to prevent release operation of said release device, and a member operable by actuating the total key whereby to unset the repeat key if the latter is in effective position.

3. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device and a member connected to operate with the main actuator and adapted to positively engage and move said lever, and means to interfere with the action of the trip means aforesaid whereby to determine the time of release action of the release device.
4. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device, and a member to positively engage and move said lever, and a repeat key having means to change the path of movement of the trip means aforesaid whereby to prevent releasing action of the trip means.
5. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device and a member connected to operate with the main actuator and adapted to positively engage and move said lever, means to interfere with the action of the trip means aforesaid whereby to determine the time of release action of the release device, a totaling control device for the accounting mechanism, and means intermediate said device and said interfering means whereby the latter is governed by the former.
6. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device, and a member connected to operate with the main actuator and adapted to positively engage and move said lever, a repeat key having means to change the path of movement of the trip means aforesaid whereby to prevent releasing action of the trip means, means to hold said repeat key in an operated position a totaling control device for the accounting

mechanism, and means intermediate the totaling control device and the repeat key to release the latter from its holding means.

7. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device, and a member connected to operate with the main actuator and adapted to positively engage and move said lever, a tiltable repeat key having means to change the path of movement of the trip means aforesaid whereby to prevent releasing action of the trip means, means to hold said repeat key in an operated position, a totaling control device for the accounting mechanism, and means intermediate the totaling control device and the repeat key to tilt said repeat key so as to release the latter from its holding means.

8. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device, a member connected to operate with the main actuator and adapted to positively engage and move said lever, a sub-total key controlling totaling functioning of the accounting mechanism, and means to lock said total key in operated position connected with and operated by said lever.

9. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device, a member connected to operate with the main actuator and adapted to positively engage and move said lever, total and sub-total keys controlling totaling and sub-totaling functioning of the accounting mechanism, and a locking device common to the total and sub-total keys and operable by said lever.

10. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action of the release device, a member connected

to operate with the main actuator and ~~and~~ of the release device, and a member connected to operate with the main actuator 20 and adapted to positively engage and move said lever, total and sub-total keys controlling totaling and sub-totaling functioning of the 5 accounting mechanism, a locking device common to the total and sub-total keys, and a connection between said trip means and its lever constituting the connection between the lever and locking device whereby the 10 latter is operated.

11. In an accounting machine, the combination of accounting mechanism, a main actuator therefor, manipulative keys for predetermining the operation of the accounting mechanism, lock means to hold said keys in operated positions, a release device for said lock means, means including a lever having trip means to cause release action 15

25

and adapted to positively engage and move said lever, a repeat key having means to change the path of movement of the trip means aforesaid whereby to prevent releasing action of the trip means, means to hold said repeat key in an operated position, a totaling control device for the accounting mechanism, a slide member intermediate the totaling control device and the repeat key to release the latter from its holding means, 30 a clear key cooperative with the accounting mechanism, and means intermediate the clear key and the slide member to actuate the latter from the clear key.

In testimony whereof I affix my signature.
AMOS H. HAWLEY.
